UNITED STATES PATENT OFFICE.

JOHN W. WILCOX, OF BEMIDJI, MINNESOTA.

QUICK-ADJUSTABLE SLIDING-JAW WRENCH.

Application filed June 23, 1923. Serial No. 647,215.

To all whom it may concern:

Be it known that JOHN W. WILCOX, a citizen of the United States, residing at Bemidji, in the county of Beltrami and 5 State of Minnesota, has invented certain new and useful Improvements in Quick-Adjustable Sliding-Jaw Wrenches, of which the following is a specification.

My invention relates to improvements in 10 wrenches of the sliding jaw type and has for its primary object the provision of such a wrench wherein the usual sliding jaw may be moved to the desired position with respect to the stationary jaw in a 15 novel and simple manner.

A further object of the invention is to provide such a wrench wherein the said sliding jaw will be maintained in positive adjusted position and wherein extremely 20 fine adjustment of the jaw may be had.

A still further object of my invention resides in the provision of such a wrench that may be manufactured and marketed at a 25 cost no greater than similar types of wrenches with which I am at present familiar.

The nature and advantages of the invention will be better understood from the following detailed description read in connection 30 with the accompanying drawing, the invention residing in the construction, combination and arrangement of parts as claimed.

In the drawing forming part of this application, like numerals of reference indicate 35 similar parts in the several views, wherein:—

Figure 1 is an elevation of one side of my improved wrench,

40 Figure 2 is a similar view with a portion of the wrench head being shown in section, and

45 Figure 3 is a detail cross sectional view taken substantially upon the line 3—3 of Fig. 1 and looking in the general direction of the arrows.

Now, having particular reference to the drawing, my novel wrench embodies a flat-like handle 5, of desirable length, formed 50 at one end with an opening 6, whereby the same may be attached to a support, and formed at its opposite end with a wide portion 7 that functions as any other wrench. This wide portion extends diagonally with

respect to the longitudinal axis of the handle 55 5 and is so formed at one end as to provide a stationary jaw 8. Extending transversely across said head 7 and directly beneath said stationary jaw 8 is an undercut groove 9, through which is freely slideable the relatively elongated tongue 10 of a sliding jaw 11. As more clearly shown in Fig. 2 the tongue portion 10 of the sliding jaw 11 is formed at its inner edge with rack teeth 12 that are extended at an angle in a direction toward the outer end of said tongue. 60

Adjacent the opposite side of the wrench head 7 from that which carries the stationary jaw 8 and communicating at one end with said undercut groove 9 is a pocket 65

13 within which is slideable a pair of relatively square-shaped plates designated respectively at 14 and 15. The edges of these plates adjacent the rack teeth of said tongue 70

10 are toothed at 14' and 15' respectively, it being noted in this connection that these teeth are inclined in a direction opposite to the inclination of the teeth of said tongue 75

10. Furthermore, the teeth upon one plate are arranged in staggered relation to the 80

teeth upon the upper plate whereby the teeth of one plate will be wholly intermeshed with the teeth of said tongue 10 the teeth of the opposite plate being only 85

partly within the teeth of said tongue for allowing adjustment to be made of the sliding jaw equivalent to one-half the distance 90

between the respective teeth 12 on said tongue 10.

The plates 14 and 15 are maintained in 95 a position to have their respective teeth in mesh with the teeth of the tongue of said sliding jaw 11 through the instrumentality of expansion coil springs 16 which are located in said pocket 13 between the opposed end of said pocket and the adjacent edges of

said plates.

The head 7 of the wrench is provided with an opening 17 immediately above the front end of the pocket 13 and positioned thereover is a cover plate secured to the head of the wrench through the medium of set screws 19 or the like. This plate 18 is provided substantially centrally with a slot 20 through which extends an elongated

100 screw 21. This screw 21 also extends through a slot in the uppermost plate 14 which is of lesser length than the slot in

105

said plate 18, this screw being finally engaged at its screw threaded end in a screw threaded opening in the lowermost plate 15. Connected to the upper end of the screw 21 and slidable upon said plate 18 is a thumb piece 22 the top surface thereof being milled. It will be apparent that a rearward movement of this plate 22 will occasion a similar movement of the plates 14 10 and 15 thereby disengaging the toothed edges of the plates from the teeth 12 of the sliding jaw tongue 10 whereby this jaw may be moved outwardly with respect to the stationary jaw 8.

15 From the foregoing it is believed by me that numerous advantages of a wrench of this character will be readily apparent to those skilled in the art and even though I have herein set forth the most practical embodiments of the invention it is nevertheless to be understood that minor changes may be made therein without departing from the spirit and scope of the invention as set forth in the appended claim.

20 25 Having thus described by invention, what

I claim as new and desire to protect by Letters Patent is:—

A wrench comprising a handle provided with a fixed jaw and having a jocket disposed at the fixed jaw, a jaw slidably mounted with relation to the fixed jaw and provided with ratchet teeth disposed toward the said pocket, plates arranged side by side in the pocket and having ratchet teeth adapted to engage the teeth of the movable jaw, springs interposed between the edges of the plates and the bottom of the pocket and serving to hold the teeth of the plates toward the teeth of the movable jaw, one of the said plates having a slot disposed transversely to the toothed edge thereof, a pin fixed to the other plate and passing through said slot and a cover plate mounted on the handle overlying the pocket and having a slot formed therein, said pin also passing through the slot of the cover plate and having at its outer end a thumb piece which covers said slot.

In testimony whereof I affix my signature.
JOHN W. WILCOX.
